UNITED STATES PATENT OFFICE.

LOUIS A. NEMCOVSKY, OF NEW YORK, N. Y., ASSIGNOR, BY MESNE ASSIGNMENTS, TO SUN TYPEWRITER COMPANY, OF NEW YORK, N. Y., A CORPORATION OF NEW JERSEY.

DESIGN FOR A PORTABLE-TYPEWRITING-MACHINE FRAME.

Application filed July 10, 1926 Serial No. 18,297. Term of patent 14 years.

To all whom it may concern:

Be it known that I, LOUIS A. NEMCOVSKY, a citizen of the United States, residing in New York city, in the county of New York and State of New York, have invented a new, original, and ornamental Design for a Portable-Typewriting-Machine Frame, of which the following is a specification, reference being had to the accompanying drawing, forming part thereof.

The figure is a perspective view of a port-

able typewriting machine frame, showing the top and one side of the new design, with a showing in dotted lines of parts of the type-writing machine to indicate the appearance of the frame when used with the operative parts of the machine.

I claim:

The ornamental design for a portable type-writing machine frame as shown and described.

LOUIS A. NEMCOVSKY.
